(57) **CLAIM**

The ornamental design for a whetstone holder, as shown and described.

DESCRIPTION

FIG. 1 is a front view of a whetstone holder showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view of a whetstone holder showing my new design; and,

FIG. 8 is another perspective view thereof.

The broken lines in the figures are for the purposes of illustrating portions of the whetstone holder, which form no part of the claimed design.
